UNITED STATES PATENT OFFICE.

CHARLES D. ROGERS, OF PROVIDENCE, RHODE ISLAND, ASSIGNOR TO THE AMERICAN SCREW COMPANY, OF SAME PLACE.

METHOD OF DIVIDING RODS OF METAL AND AT THE SAME TIME POINTING AND THREADING THE ADJACENT ENDS THEREOF.

SPECIFICATION forming part of Letters Patent No. 429,388, dated June 3, 1890.

Application filed March 31, 1888. Serial No. 269,107. (No model.)

To all whom it may concern:

Be it known that I, CHARLES D. ROGERS, a citizen of the United States, residing at Providence, in the county of Providence and State 5 of Rhode Island, have invented certain new and useful Improvements in the Method of Dividing a Rod of Metal and at the Same Time Pointing and Screw-Threading the Adjacent Ends Thereof; and I do hereby declare the 10 following to be a full, clear, and exact description of the invention, such as will enable others skilled in the art to which it appertains to make and use the same, reference being had to the accompanying drawings, 15 and to letters of reference marked thereon, which form a part of this specification.

In an application for Letters Patent filed by me December 24, 1886, Serial No. 222,517, and allowed February 16, 1888, I have de- 20 scribed and claimed mechanism for simultaneously dividing a rod of metal transversely into two pointed sections, each point portion having a screw-thread impressed therein by the same operation.

25 My present application is a continuation of the one just referred to; and it consists of the method or process embodied therein but not claimed.

I am aware that rods have heretofore been 30 divided transversely by passing them between moving dies, which reduce and elongate the portion of the stock acted upon. My improvement upon such former methods resides in rolling or impressing a flattened V-shaped 35 groove into and around the periphery of the rod at the point where it is to be severed, the continuation of the rolling operation also impressing a helical groove or screw-thread into the contiguous surfaces of the circumferential 40 V-shaped groove, and then severing the rod, thereby simultaneously producing from one rod two shorter rods, each having a screw-threaded cone-shaped point.

45 By means of my improvement I am enabled to double the production of screws or bolts as compared with the process of rolling and threading the points singly.

50 Another advantage resulting from my improvement is that I dispense with the turning and screw-cutting operations as commonly

practiced in the manufacture of the larger sizes of wood-screws, coach-screws, &c.

In order to illustrate my improved method of producing two contiguous screw-threaded cone-shaped points upon a rod at one operation, I have prepared the accompanying two sheets of drawings, in which—

Figure 1, Sheet 1, represents a plan view of a machine embodying said method. Fig. 2 is an enlarged plan view showing the form and arrangement of the dies. Fig. 3, Sheet 2, is a face view of one of the dies, the other being reversely arranged and indicated by dotted lines, showing a rod headed at each end in position to be acted upon by the dies. Fig. 4 is a transverse sectional view taken through the dies, showing their relation to the rod immediately preceding their action upon it. Fig. 5 is a similar view, the dies having been advanced; thereby forming the rolled cone-shaped peripheral groove in the center of the rod and a consequent lengthening of the same. Fig. 6 is a similar view of the parts, showing the action of the dies upon the rod at the termination of their work, thereby simultaneously producing a screw-thread upon each of the contiguous points and practically severing the rod. Fig. 7 is a partial transverse sectional view taken on line *s s*, Fig. 3, through the V-shaped reducing portion of one of the dies. Fig. 8 is a similar view of the die, taken through the first or entering portion of the thread forming part of the die on line *o o*; and Fig. 9 is a sectional view of the same, taken on line *x x*, showing the progressive forming 85 of the screw-thread.

In carrying out my improvements I employ two oppositely mounted and operated dies *A*, each having an ungrooved projection *D* on its face, the shape of which closely approximates a half-pyramid cut longitudinally through its major axis. This portion of the die serves to impress a correspondingly-shaped peripheral groove into the metal rod to be acted upon, thereby obviously lengthening the rod 95 somewhat, as clearly shown in Figs. 4 and 5, the former figure showing a rod *a* having a head *h* at each end, the latter figure representing the rod after the V-shaped groove is impressed therein. The highest part of the

die D is about equal to the semi-diameter of the rod. D' indicates the thread-forming or grooved portion of the die, the same being a continuation of the ungrooved portion D. 5 The cross-sectional form or contour of the grooved die, excepting the grooves and ribs, is the same throughout its length, the sides of the die at the point of intersection forming the longitudinal ridge or apex e. The grooves 10 t are cut obliquely into the sides of the die so as to produce ribs narrow at their commencement, where they join the ungrooved portion, which gradually increase in width to form the desired size of thread, as common to rolling 15 screw-threads. In the drawings, Fig. 1, I have represented the main dies A connected each with a crank m by means of a link r, o indicating the driving-shafts. The dies are mounted in frames E, plates or gibs f serving to maintain 20 the dies in position.

From the foregoing description it is evident upon operating the dies toward each other (a rod being in position between them, as shown in Fig. 3) that the center point c first engages 25 the rod and impresses a slight V-shaped groove therein. The continued movement of the dies will next produce a deep V-shaped groove and nearly sever the rod, as shown in Fig. 5, wherein the ungrooved portions D have just completed 30 their work. The further continued movement of the dies next gradually impress the ribs of the grooved portion into the periphery of the two cones or pointed portions of the rod, when at the termination of the stroke the dies 35 will have simultaneously impressed a screw-thread into each half of the rod and severed

it, substantially as shown in Fig. 6. The blanks thus provided with a screw-threaded point may be next fully threaded and finished, as usual—that is, by submitting them to 40 the action of the dies of a bolt or screw cutting machine. The screw-threaded point serves as a "leader" in automatically guiding the blanks to the main threading-dies.

In the event of large sizes of wire being 45 used I preferably heat the stock at the point to be operated upon by the combined pointing and threading dies.

By means of my improvement it is apparent that the production of screws or bolts may 50 be greatly increased as compared with the usual method of first pointing each rod singly, then threading the points, and finally screw-threading the stem or body of the bolt.

I claim as my invention—

The improvement, substantially as herein-before described, in the manufacture of screws or bolts, consisting, first, in suitably preparing the rod of metal, next rolling a plain V-shaped peripheral groove or depression into 60 the rod's surface, thereby elongating the rod toward both ends and nearly severing it, and finally simultaneously rolling a screw-thread on the two adjacent sides of the said V-shaped groove and severing the rod.

In testimony whereof I have affixed my signature in presence of two witnesses.

CHARLES D. ROGERS.
